UNITED STATES PATENT OFFICE

RICHARD J. HAUG, OF NASHUA, NEW HAMPSHIRE

DISPLAY STAND

Application filed October 13, 1930, Serial No. 488,245. Renewed July 20, 1932.

This invention relates to display stands that are especially adapted for use in retail stores in supporting tiers of boxes in which goods are displayed.

5 One of the objects of the present invention is the provision of a display stand that is light in weight, portable, that can be disassembled, and is capable of being arranged in various configurations and is composed of 10 relatively few parts that can serve a variety of purposes, and which is cheap and durable.

Another object of the invention is generally to improve the construction of display stands.

15 Fig. 1 is a side elevation of a stand embodying the present invention.

Fig. 2 is a front elevation of the stand of Fig. 1.

Fig. 3 is a sectional elevation taken along line 3—3 of Fig. 2.

20 Fig. 4 is a sectional elevation taken along line 4—4 of Fig. 3.

Fig. 5 is a perspective view of an end of one of the rungs.

25 Fig. 6 is a detail illustrating the manner in which the rung is locked detachably in a cooperating manner.

Fig. 7 is a perspective view of one of the top brackets.

30 Fig. 8 is a perspective view of one of the shelves.

Fig. 9 is a perspective view of a supporting post.

Fig. 10 is a perspective view of a post extension.

35 Fig. 11 is a perspective view of one of the rungs.

Fig. 12 is a perspective view of one of the shelf supporting rails.

40 Fig. 13 is a side elevation of a modified disposition of the stand.

Fig. 14 is a side elevation of a further modified arrangement of the stand.

Fig. 15 is a side elevation illustrating the manner of connecting duplicate stands together in spaced relation.

45 The display stand embodying the present invention, and, as illustrated in Figs. 1 and 13, is composed of a pair of top members 20, Fig. 7, and a number of duplicate shelf members 22, Fig. 8, together with duplicate rails

24, Fig. 12, rungs 26, Fig. 11, and supporting posts 28, Fig. 9, and the extensions 30 thereof, see Fig. 10.

The top member 20 is composed of sheet metal and is of narrow channel shape. Said member has the flat top wall 32 and the reflexed depending and relatively deep side walls or flanges 34. Notches 36 are formed in the bottom edges of said side walls and have tapered side edges 38. Pairs of key-hole slots 40 are formed in said side walls at the opposite ends of said top member, each slot comprising the circular aperture 42 and the elongated notch 44 which opens into said circular aperture, the notches being extended horizontally inwardly toward the vertical median line of the member. There are other pairs of vertically extended keyhole slots 46 at the bottom outer edges of the side walls. There is another pair of vertically extended keyhole slots 48 located in the median vertical line of the member above the notches 36. The keyhole slots are adapted to receive certain rungs 26, the rungs each having two sets of diametrically opposed and axially spaced notches 50 in the ends thereof. The sets of notches are spaced apart by the distance between the side walls 34 and the thickness of material between opposed notches being less than the width of the elongated portion 44 of the keyhole slot. The circular portion 42 of the keyhole slot is large enough to receive the full diameter of the rung. Thus when the end of the rung is entered in the circular portion of the slot, and thence is moved downwardly into the elongated portion wherein the side walls 34 are located in the slots 50, the rung and the top member are locked together against axial displacement.

The top member is also provided with integral depending lips 52 which lie within the channel of the top member, in the middle thereof, and are spaced from the side walls 34.

50 The shelf member 22 comprises a channel member having the flat top wall 54 and the reflexed depending parallel side walls or flanges 56. The spacing of the side walls is

the same as the spacing of the flanges 34 of the top member. The top wall 54 at one end is provided with a square passage 58 therethrough. The end edges 60 of said flanges 5 extend downwardly under the top wall 54 at a slight inclination from the perpendicular with respect thereto and the opposite end edges 62 of said flanges are parallel with the edges 60. Keyhole slots 64 are formed in the 10 flanges under the top 54 and adjacent the inclined edges 60 of the flanges and extend in parallel relation with said top. Notches 66 are formed in the bottom edges of the flanges adjacent the side edges 60 and are perpendicular to the top wall 54. Keyhole slots 68 which are parallel with the edges 60 are formed in the flanges near the bottom edges thereof and in the middle thereof.

In assembling the stand to form the construction illustrated in Fig. 1, two top members 20 are employed to form the ends of the stand. Each top member is supported upon a post 28 and its cooperating extension 30. Both posts 28 and 30 are of square tubular metal formation. The upper end of post extension 30 is located between the flanges 34 of the top member and bears against the lower face of the top wall 32 thereof; and the lips 52 of said top wall are located within the open end of the post as is shown in Fig. 20. The space between the side walls 34 of the top member are about equal to the width of the post so that the top member cannot rotate on the post. The post extension 30 has a passage 70 therethrough which is in register with the keyhole slots 48. A rung 26 passes loosely through the passages 70 of the end pair of these posts and also through said keyhole slots in the top members, thereby locking the posts to the top members and also locking the top members in spaced relation. The post extension 30 has a reduced end section 72 which fits in the open upper end of the post 28 and each of the two posts is provided with such an extension member. The upper end of each post has a rung passage 74 which is not necessarily used in the construction shown in Fig. 1, but receives the rung that passes through the passage 70 when the extension is eliminated in constituting the stand of Fig. 13. A pair of shelf members 22 are disposed on opposite sides of the post extensions and have their flanges overlapping and a rung is passed through the aligned keyhole slots 68 of both shelf members, thereby locking the shelf members together. The lower end of the post 28 has an axially-elongated notch 75 30 therein in which said rung is located; and the top edges of the top walls 54 bear in opposite directions against the post so that the posts and shelf members are connected together in a stable manner. The shelf members are thus arranged to constitute support-

ing feet for the stand. The stand rests upon the edges 60 of the flanges of the shelves.

Four spaced, parallel, shelf-supporting rails 24 are connected with the ends of the top members in the inclined manner illustrated in Fig. 1. Each rail consists of a metal tube of square cross section and has a rung receiving passage 76 at one end and other rung receiving passages 78 that are located within the channel space between the flanges 34 of a top member at the outer end thereof and with the rung passage 76 in line with a pair of keyhole slots 46. A rung 26 is passed through the similar keyhole slots in the two top members and loosely through the passages 76 in a pair of rails on the same side of the stand whereby to lock the rails to the top members. A plurality of shelves 22 are arranged on each rail with the rail passing through the square opening 58 in the top wall 54 in each shelf. Other rungs 26 are extended through the openings 78 in each pair of rails at the same side of the stand and each shelf is seated upon the end of a separate rung. The rungs lie in the notches 66 of the shelves and the opposed ends of the flanges at said notches are located in the slots 50 of the rungs whereby to hold the shelves in the horizontal positions illustrated in Fig. 1. Pairs of shelves are located at the same horizontal level and are adapted to support suitable open-top goods-containers as the boxes A. The stand illustrated in this figure is relatively high and the rails have a small inclination. The stand can be made shorter in height and the rails 24 disposed at greater inclination, if desired. Such a disposition is illustrated in Fig. 13. In this construction, the top members 20 are supported only upon the posts 28 in an obvious manner, the post extensions 30 being eliminated. With this construction the tops of the shelf members that constitute the supporting feet of the stand are received within the notches 36 in the flanges 34 of the top members. The shelves 22 are arranged on the rails with the rails lying between and in approximate engagement with the flanges 56 and the rungs 22 being keyed to the flanges in the slots 66, with the exception of the lowermost slots 68 so that the bottom edges 67 of the flanges 56 rest upon the floor, and being parallel with the top wall 54, support the lowermost shelf in horizontal position. The display boxes A rest upon and between the shelves in the manner illustrated in the dotted lines. The lowermost box rests entirely upon the lowermost pair of shelves while the forward edges of the upper boxes can rest upon the rear edges of the lower boxes. The ends 62 of the flanges 56 of a lower shelf abut against the edges 60 of the flanges of an upper shelf so that the shelves are locked against swinging in a clockwise direction away from the rails about the rungs to which they are connected. The end edges 70 75 80 85 90 95 100 105 110 115 120 125 130

35 of the flanges 34 of the top members are inclined downwardly and inwardly toward the vertical median line of the top members in such manner that the ends 62 of the upper 5 most shelf engages them for the purpose of holding the uppermost shelf against similar displacement.

If desired two display stands can be connected together in spaced relation to form a 10 long table in the manner illustrated in Fig. 15. A rail member 24 is extended between a pair of top members on the same side of the stand and has ends located within the flanges 15 of the top members which are connected with the rungs that pass therethrough, thereby to maintain the two stands in spaced relation.

A further modified arrangement of stand is illustrated in Fig. 14. In this construction the top members 20 are eliminated. In 20 this construction the rung that passes through the tops of and connects the posts 28 also passes through the keyhole slots 64 in a pair of shelf members. The shelf members are supported in inclined position by a 25 post extension 30 which is disposed on a rung that is located in the keyhole slot 68 of the shelf members and that serves to connect the pair of shelf members. The reduced portion 72 of the post extension is located 30 within the opening 58 of one of the shelf members that constitutes a foot for the stand and has a slot 80 in its end in which a portion of the top wall 54 is received whereby to 35 support the top shelf in the position illustrated. A bottom shelf can be carried by the post extension, the post extension being extended through the passage 58 in the top wall of the shelf and the outer end of the 40 shelf resting upon the floor.

It will be apparent that still other modifications can be constructed, all without departing from the spirit of the invention.

I claim:

45 1. In a display stand, the combination of a pair of inclined parallel rails, shelf members carried by said rails each comprising a top plate and depending side plates between which a rail is located, and means connecting said rails in spaced relation.

2. In a display stand, the combination of a pair of inclined parallel rails, shelf members carried by said rails each comprising a top plate and depending side plates between 55 which a rail is located, and means connecting said rails in spaced relation, said connecting means being passed through the depending side plates of opposed shelves on said rails and constituting means securing said shelves to said rails.

3. In a display stand, the combination of spaced upright supporting posts, top members at the upper ends of said posts, means connecting said top members in spaced relation, a pair of spaced inclined parallel rails

connected to said connecting means, rungs extended between and connecting said rails, and shelf members each carried by a rail and connected thereto by a rung.

4. In a display stand, the combination of 70 a pair of spaced parallel inclined rails, a separate shelf member on each rail comprising a top wall and depending side walls which closely overlie opposite sides of an associated rail, and a rung which is passed through said rails and the side walls of both shelves, said side walls and rung having co-operating means which connects them together against unintentional detachment.

5. In a display stand, the combination of 75 a pair of spaced parallel inclined rails, a separate shelf member on each rail comprising a top wall and depending side walls which closely overlie opposite sides of an associated rail, and a rung which is passed through said rails and the side walls of both shelves, said side walls and rung having co-operating means which connects them together against unintentional detachment, said connecting means comprising keyhole 80 slots in said side walls in which said rung is located, and opposed slots in said rung in which said side walls at said keyhole slots are located.

6. In a display stand, the combination of 85 a pair of spaced inclined parallel side rails, shelf members carried separately by each of said rails, and a rung passed through said rails and having connections with said shelves which secure said shelves, rung and side rails against unintentional disconnection.

7. In a display stand, a top member including a top wall and spaced side walls, an upright supporting post located between said side walls, a cylindrical connecting member passed through said side walls and through said post, supporting feet on the bottom of said post, an inclined rail having its upper end connected with the side walls of said top member, and shelves carried by said rail.

8. In a display stand, a top member including a top wall and spaced side walls, an upright supporting post located between said side walls, a cylindrical connecting member passed through said side walls and through said post, supporting feet on the bottom of said post, an inclined rail having its upper end connected with the side walls of said top member, and shelves carried by said rail, said shelves having top walls and depending spaced side walls between which said rail is located, and cylindrical connecting means passed through said side walls and said rail.

9. In a display stand, the combination of a top member having a top wall and spaced depending side walls, said top member having a pair of opposed depending ears which lie between said side walls, an upright hollow post of square cross section having its upper end 125

located between said side walls and in engagement therewith with said ears located within the open top of said post, cylindrical connecting means passed through said side walls 5 and said post below said ears, supporting feet on the bottom of said post, and shelf members carried by said top member.

10. In a display stand, the combination of a top member, an upright supporting post 10 therefor, and supporting feet on the bottom of said post, said feet each comprising a member having an end wall and spaced parallel side walls which are disposed on opposite sides and in overlapping relation with each 15 other and said post, and means which is passed through said side walls and post and connects the aforesaid parts together.

11. In a display stand, the combination of a top member, an upright supporting post 20 therefor, and supporting feet on the bottom of said post, said feet each comprising a member having an end wall and spaced parallel side walls which are disposed on opposite sides and in overlapping relation with 25 each other and said post, and means which is passed through said side walls and post and connects the aforesaid parts together, said means comprising a cylindrical connecting member, and the lower end of said supporting post having a notch therein in which said connecting member is loosely received.

12. In a display stand, the combination of a top member having a top wall and spaced 30 depending side walls provided with aligned notches in the bottom edges thereof, an upright supporting post which is disposed between said side walls and said notches and has a connection with said top member, and a pair 35 of supporting feet at the bottom of said post each comprising a member having an inclined end wall and spaced side walls, said members being oppositely disposed with their side walls lying on opposite sides of said post and the upper ends of their inclined end walls 40 received in said notches.

13. In a display stand, a top member comprising a top wall and spaced depending side walls, said top wall having means located in the middle thereof for connection with a 50 support and said side walls having a plurality of aligned connecting-member receiving openings therethrough.

14. In a display stand, a top member comprising a top wall and spaced depending side 55 walls, said top wall having means located in the middle thereof for connection with a support and said side walls having a plurality of aligned connecting-member receiving openings therethrough, said openings being in the form of keyhole slots.

15. In a display stand, a shelf member comprising a top wall and spaced parallel depending side walls, said side walls having 60 a plurality of aligned connecting-member re-

ceiving apertures therein and also having a rail-receiving opening in said top wall at one end thereof.

16. In a display stand, the combination of a supporting post, a top member on the upper end thereof, an inclined rail having its upper end connected with said top member, and a shelf on said rail, said shelf having a top wall and spaced depending side walls between which said rail is located, and a rung passed through said rail, said shelf having a pair of aligned apertures in its side wall in which said rung is adapted to be located. 70

17. In a display stand, the combination of a supporting post, a top member on the upper end thereof, an inclined rail having its upper end connected with said top member, and a shelf on said rail, said shelf having a top wall and spaced depending side walls between which said rail is located, and a rung passed through said rail, said shelf having an aperture in its top wall near one end thereof through which said rail is extended and having aligned slots in the bottom edges of its side walls in which said rung is located. 80

18. In a display stand, the combination of a supporting post, a top member on the upper end thereof, an inclined rail having its upper end connected with said top member, and a shelf on said rail, said shelf having a top wall and spaced depending side walls between which said rail is located, and a rung passed through said rail, said shelf having an aperture in its top wall near one end thereof through which said rail is extended and having aligned slots in the bottom edges of its side walls in which said rung is located, said shelf also having a pair of aligned rung-receiving apertures in its side walls intermediate the ends of the shelf. 90

19. In a display stand, the combination of a pair of top members each having a top wall and spaced depending side walls, a rung extended through the side walls of said top members and securing them in spaced relation, upright supporting posts located between the side walls of said top members and on said rungs, supporting feet at the end of said posts, inclined parallel rails having their upper ends located between the side walls of said top members at the end thereof, rungs passed through said side walls and said rails and connecting them together, other rungs passed through and connecting said rails between the ends thereof and shelves each independently carried by a rail and each having a top wall and depending side walls which are disposed on opposite sides of the rail and have aligned openings at their lower ends 105 in which a rung is located. 110

20. In a display stand, the combination of a pair of top members each having a top wall and spaced depending side walls, a rung extended through the side walls of said top 120

members and securing them in spaced relation, upright supporting posts located between the side walls of said top members and on said rungs, supporting feet at the end of 5 said posts, inclined parallel rails having their upper ends located between the side walls of said top members at the ends thereof, rungs passed through said side walls and said rails and connecting them together, other rungs

10 passed through and connecting said rails between the ends thereof, and shelves each independently carried by a rail and each having a top wall and depending side walls which are disposed on opposite sides of the rail and 15 have aligned openings at their lower ends in which a rung is located, the top wall of each shelf also having a passage therethrough near one end of the shelf through which a rail is extended.

20 21. In a display stand, a shelf comprising a sheet metal member having a top wall and spaced parallel depending side walls having a portion of their bottom edges parallel with said top wall and another portion inclined 25 upwardly toward said top wall, the end edges of said side walls being parallel and being inclined at other than a right angle with respect to said top wall, and said side walls having sets of aligned connecting-member receiving 30 passages therethrough.

22. In a display stand, the combination of a pair of top members each having a top wall and spaced depending side walls, an upright post located between the side walls of each 35 top member, means extended between said top members connecting them and said posts together, supporting feet on said posts, rails connected with said top members, shelves on said rails, each shelf having a top wall and spaced depending side walls, and means connecting each shelf separately to its associated rail, said shelves and said foot members being identical.

23. In a display stand, the combination of 45 a pair of top members each having a top wall and spaced parallel depending side walls, a plurality of shelf members each having a top wall and spaced parallel depending side walls, a pair of upright supporting posts located each between the side wall of a separate top member, a connecting member extended through aligned apertures in the side walls and posts of all top members, a pair of foot members located on opposite sides of each 55 supporting post and having their side walls overlapping said posts, a rung which is passed through said overlapping side walls and said posts and which connects them together, a pair of rails having their upper ends 60 disposed between the similar ends of the side walls of said top members, rungs passed through aligned apertures in said side walls and rails and connecting said rails and top members together, said shelf members being 65 located on said rails between said side walls,

and rungs passed through said rails intermediate their ends and through aligned passages in the side walls of said shelf members, each shelf member on the same rail being engaged with a separate rung, said shelf and foot members being identical and interchangeable. 70

In testimony whereof, I have signed my name to this specification.
